UNITED STATES PATENT OFFICE.

GASPARD LAPORTE, OF PAWTUCKET, AND OCTAVE LAPORTE, OF CENTERVILLE,
RHODE ISLAND.

SHOEMAKER'S JACK.

1,384,903.

Specification of Letters Patent. Patented July 19, 1921.

Application filed October 29, 1919. Serial No. 334,205.

To all whom it may concern:

Be it known that we, GASPARD LAPORTE and OCTAVE LAPORTE, citizens of the United States, and residents of Pawtucket and Centerville, respectively, in the counties of Providence and Kent, respectively, and State of Rhode Island, have invented certain new and useful Improvements in Shoemakers' Jacks, of which the following is a specification.

This invention relates to shoemakers' jacks; and has for its object to provide a simple, practical and effective jack of this character on which boots or shoes are held while being repaired. This jack is adapted to receive and bind the shoe in position while being operated upon, means being also provided whereby the member supporting the last may be readily rotated to present the work in the most convenient position to be operated upon.

A further object of the invention is to provide simple and effective means whereby the last-supporting member may be readily locked in the standard against relative rotation.

With these and other objects in view, the invention consists of certain novel features of construction, as will be more fully described, and particularly pointed out in the appended claim.

In the accompanying drawings:

Figure 1— is a side elevation with one of the halves of the standard member removed, showing the internal mechanism.

Fig. 2— is an edge view showing the standard member in section.

Fig. 3— shows a portion of the standard and the slot and notch for receiving the tension-applying foot-treadle.

Fig. 4— is a top view of the standard, showing the trunnion member in section; also illustrating the side notches through which the arms of the tension connector

passes.

Fig. 5— is a face view of the locking cam lever.

Fig. 6— is a sectional view on line 6—6 of Fig. 5, showing the cam on the face of the lever.

Referring to the drawing, 10 designates the standard member of a shoemaker's jack, which is preferably tubular in form and made in halves, which halves are bolted to-

gether through the ears 11, the standard being supported on a suitable base. Adjacent its lower portion this standard is cut out forming an elongated slot 12 for the purpose of receiving the treadle-member presently described.

The lower portion of this slot is offset forming a treadle-retaining notch 13.

The treadle member is provided with a body portion 14 mounted to slide longitudinally in the tubular standard and this body portion is provided with a laterally-extending foot-engaging projection 15 which extends out through the slot and is adapted to be carried to one side to engage the notch 13 after having been pressed downwardly by the foot of the operator. The body of this treadle is provided with an eye 16 for the reception of one end of the tension spring 17.

On the upper end of this tubular standard is mounted an extension member 18 whose lower end is provided with a trunnion portion 19 which projects into the tubular standard, while the upper end of this extension member is formed tapering as at 20 to receive the last 21 which is mounted upon it.

Looped over this last is a strap 22 which is adapted to be raised sufficiently when the treadle member is released from the notch, to permit a shoe, as shown in dotted lines, 85 to be readily positioned on the last after which the strap is slipped into place over the shank of the shoe to bind it securely in position.

The lower ends 23 of this strap are looped through the eyes 24 at opposite ends of the U-shaped tension member 25 the arms of which tension member extend through recesses 26 formed in opposite sides of the trunnion 19 and a swivel 27 is interposed 95 between the spring 17 and the tension member 25, whereby the extension member 18 may be rotated with the last to move the latter into any desired position without twisting the connecting parts.

It is found in practice necessary to provide simple and effective means for binding and retaining this trunnion portion 19 in the tubular standard against rotation while operating upon a shoe.

To accomplish this in a simple and effective way, we have provided a cam-shaped portion 28 on one face of the ear 11, see Fig.

4, and we have also provided cam-shaped faces 29 on the inner face of the lever 30. A binding bolt 31 passes through the ears and said lever whereby a downward movement 5 of said lever springs the parts of the tubular standard toward each other under action of the cam surfaces 28 and 29 thereby binding and firmly securing the trunnion portion 19 in this tubular member against relative rotation.

This jack is extremely simple and inexpensive in construction and effective in its operation and by its use a shoemaker may readily adjust it to his requirements and 15 securely bind the work in operating position thereon.

The foregoing description is directed solely toward the construction illustrated, but we desire it to be understood that we 20 reserve the privilege of resorting to all the mechanical changes to which the device is susceptible, the invention being defined and

limited only by the terms of the appended claim.

We claim:

A shoemaker's jack comprising a tubular standard, an extension member having a trunnion at its lower end rotatably mounted in said standard, a last mounted on the upper end of said extension, said trunnion being provided with longitudinally-disposed recesses in opposite sides thereof, a foot treadle, said standard being provided with a retaining notch to receive said treadle, a strap looped over said last, a U-shaped connection member extending through said recesses, a spring and a swivel interposed between said treadle and said connection-member, and means for binding said trunnion in adjusted position.

In testimony whereof we affix our signatures.

GASPARD LAPORTE.
OCTAVE LAPORTE.
